UNITED STATES PATENT OFFICE.

FREDERICK SCHWARTZ, OF BROOKLYN, NEW YORK, ASSIGNOR TO ROBERT FINDLAY MANUFACTURING COMPANY, INC., OF BROOKLYN, NEW YORK, A CORPORATION OF NEW YORK.

DESIGN FOR A TABLE FOR RADIO RECEIVING SETS OR THE LIKE.

Application filed October 1, 1928. Serial No. 28,334. Term of patent 7 years.

To all whom it may concern:

Be it known that I, FREDERICK SCHWARTZ, a citizen of the United States, and a resident of the borough of Brooklyn, city of New York, county of Kings, and State of New York, have invented a new, original, and ornamental Design for Table for Radio Receiving Sets or the Like, of which the following is a specification, reference being had to

the accompanying drawing, forming a part thereof.

The figure of said drawing is a perspective view of a table of my new design.

I claim:

The ornamental design for a table for radio receiving sets or the like, as shown.

FREDERICK SCHWARTZ.
